(57) **CLAIM**

I claim the ornamental design for a dispensing closure, as shown and described.

DESCRIPTION

FIG. 1 is a perspective view of a dispensing closure in accordance with my design.

FIG. 2 is a top plan view of the dispensing closure, the bottom of the dispensing closure forming no part of the claimed design.

FIG. 3 is a front elevational view of the dispensing closure. FIG. 4 is a side elevational view of the dispensing closure taken from the right in FIGS. 2 and 3, the opposing side elevational view being a mirror image of FIG. 4; and, FIG. 5 is a rear elevational view of the dispensing closure, the hinge being shown in phantom in FIGS. 4 and 5 for environment only and not included in the claimed design.
